UNITED STATES PATENT OFFICE.

RUSSELL FRASER, OF NEW YORK, N. Y.

DESIGN FOR A SPOOL-HOLDER.

SPECIFICATION forming part of Design No. 25,859, dated August 4, 1896.

Application filed June 11, 1896. Serial No. 595,223. Term of patent 7 years.

To all whom it may concern:

Be it known that I, RUSSELL FRASER, a citizen of the United States, residing at New York city, in the county and State of New York, have invented and produced a new and original Design for a Spool-Holder, of which the following is a specification, reference being had to the accompanying drawing, forming part thereof, which represents a perspective view of a spool-holder embodying the features of the design.

The design consists in a main surface A and an auxiliary surface B at an angle to and

located beneath the main surface, being of less length than the said main surface, together with wings C, appearing as continuations of the extremities of the main surface and at a right angle to the same.

I claim—

The design for a spool-holder, substantially as herein shown and described.

RUSSELL FRASER.
